UNITED STATES PATENT OFFICE.

SIMON W. FARBER, OF BROOKLYN, NEW YORK.

DESIGN FOR A FERN-DISH OR SIMILAR ARTICLE.

52,985.

Specification for Design.

Patented Feb. 11, 1919.

Application filed March 4, 1918. Serial No. 220,400. Term of patent 7 years.

To all whom it may concern:

Be it known that I, SIMON W. FARBER, a citizen of the United States, residing at Brooklyn, in the county of Kings and State of New York, have invented a new, original, and ornamental Design for a Fern-Dish or Similar Article, of which the following is a specification, reference being had to the accompanying drawing, forming a part thereof.

In the drawings,

Fig. 2 shows an enlarged perspective view of the ornament shown in Fig. 1.

I claim:—

The design for a fern dish or similar article as shown.

In testimony whereof I hereunto affix my signature.

SIMON W. FARBER.
